APPARATUS FOR THE PREPARATION OF
PAPER STOCK AND THE LIKEEdwin Cowles, Hopewell, N. J., assignor to The
Cowles Company, Princeton, N. J., a corpora-
tion of New Jersey

Application January 22, 1937, Serial No. 121,837

9 Claims. (Cl. 92—23)

This invention relates to apparatus adapted particularly for use in the preparation of paper stock, but which may also be used for other purposes such as disintegrating, dissolving, mixing and screening solids suspended in liquids.

In the preparation of paper stock for use in paper making machines it is desirable to submit the fibrous material, suspended in water, of course, to several types of treatment, each having a different purpose. Thus, the material must be completely defibered, or the defibered material must be separated from any undefibered material, it must be cleaned and freed of waste and impurities, and usually it must be submitted to what is ordinarily called a refining action, by which is meant a grinding or crushing of the fibers in order to improve their web forming characteristics. In the past a series of pieces of apparatus have been required to perform these various operations such as beaters, settling troughs, screens, centrifuges, Jordans, etc., and in view of the fact that the consistency of the stock had to be varied for the various operations, means for thinning and thickening the stock had to be provided.

It is an object of the present invention to provide a machine capable of performing either wholly or in part, either some or all of the aforesaid purposes. For example, it is an object of the invention to take raw material such as waste paper, disintegrate and defiber the same, separate the defibered material from the undefibered material and from various types of waste and impurities, while at the same time refining the fibrous material, so as to deliver from the machine stock which is capable of being used directly in paper or board making machines. Alternatively, the said operations may be performed in part, depending upon the type of raw material being treated and the results which it is desired to secure.

Other objects and advantages of the invention will appear hereinafter.

A preferred embodiment of the invention selected for purposes of illustration is shown in the accompanying drawings, in which,

Figure 1 is a longitudinal section through the apparatus.

Figure 2 is a top plan view of the lower section of the casing, the screen being partly broken away.

Figure 3 is a section on the line 3—3 of Figure 2.

Figure 4 is a side elevation of the impeller unit.

Figure 5 is a top plan view of the same.

Figure 6 is an end elevation illustrating one of the scrapers.

Figure 7 is a bottom plan view in the opening and the spinning screen unit therein.

Figure 8 is an enlarged section on the line 8—8 of Figure 7.

Referring to the drawings, the apparatus comprises a casing formed of an upper section 1, an intermediate section 2 and a lower section 3, which said sections may be secured together in any convenient manner. The said casing provides an impeller chamber 4, within which is mounted the impeller 5, said impeller being secured to the shaft 6 for rotation therewith as by the key-way 7. The shaft 6 may be rotated by any suitable source of power such as an electric motor (not shown) which may be mounted on a frame 8, in order that the armature shaft may be connected directly to the shaft 6.

An annular chamber 10 is formed in the lower casing section 3, and the said chamber is separated from the impeller chamber 4 by a perforated screen 11 in the form of a flat disk supported on the grid 12 as best illustrated in Figure 2. The said annular chamber 10 is provided with an outlet opening 13 through which material entering the chamber 10 through the screen 11 may be discharged.

A similar annular chamber 15 is formed in the upper casing section 1, and the said chamber 30 is also separated from the impeller chamber 4 by a perforated screen 16 supported by the grid 17. The said chamber 15 is provided with an outlet opening 18 through which material entering the chamber 15 from the impeller chamber 35 4 may be discharged. If desired, the perforations of the screen 11 may be of a different size from those of the screen 16 in order that different grades or classes of stock may be removed separately from the chambers 10 and 15, it being understood that the smaller the perforations in the screen, the shorter the fibers which will pass through.

The impeller 5 is provided with a plurality of vanes 20 extending radially from the axis of 45 the impeller, and the said vanes carry scrapers 21 adapted to bear against the screens 11 and 16 as the impeller is rotated, thereby performing several useful and important functions in the operation of the machine. In the preferred embodiment illustrated, the said scrapers are made of resilient material such as relatively thin spring steel strip, and are bolted to the impeller vanes, as illustrated in Figure 6, in such manner that the springiness or resilience of the metal causes 50 55

- the leading edge of the scraper to bear against the screen. The perforations in the screen are preferably rather small, ranging, for example, from $\frac{1}{16}$ ", or even less for special purposes, to 5 $\frac{1}{8}$ ", and the cooperation of the scrapers 21 with these relatively small perforations serves to clear the perforations to permit material to pass through and also provides an efficient defibering and refining action on the fibrous material. It 10 will be understood in this connection that the consistency of the stock in the impeller chamber is higher than that of the stock entering the chamber or of the stock leaving the chamber, the screens having a thickening effect on the stock. 15 It will also be understood that the higher the consistency of the stock in the impeller chamber, within reasonable limits, the greater the defibering and refining action which takes place. The degree of thickening effected by the screens is 20 dependent on the size of the screen perforations, and by the rate of flow through the screens, and may be adjusted, as desired, by varying the size of the screen perforations or by adjusting the rate of flow. 25 The amount of the refining action may be increased, if desired, by re-cycling material which has passed through the screen back to the impeller chamber for further treatment, and a very simple and effective means for accomplishing this 30 purpose is illustrated in Figure 1, and comprises an adjustable plug 24 which cooperates with a large screen opening 25. It will be understood that the pressure created by the impeller 5 increases toward the periphery of the casing, and that it is greater at the outer edge of the screen 16 than it is at the opening 25. Consequently, if the plug 24 is backed off to permit material to pass through, the direction of flow will be from the chamber 15 to the chamber 4. In this manner, by providing a plurality of plugs 24 and 35 openings 25, a considerable quantity of material may be re-cycled, if desired, and the refining action may be increased thereby. 40 In the preparation of paper stock, and particularly in the preparation of stock from waste paper, there are two types of waste material which 45 it is desirable to eliminate in order to improve the quality of the stock. These two types may be classified roughly as heavy materials and light 50 materials, the heavy materials comprising such waste as pieces of metal, glass, sand and the like, while the light materials include such waste materials as rubber bands, wood slivers, Cellophane and the like. In eliminating or removing these 55 two classes of waste materials, the centrifugal effect of the rapid rotation of the impeller is availed of to some extent. Thus an outlet opening 27 for the discharge of waste materials of a heavy nature is provided at the periphery of the 60 casing and a discharge opening 28 for the discharge of light waste materials is provided near the axis of the impeller. Furthermore, the impeller itself is constructed to take advantage of the centrifugal effect. Thus the impeller is provided with a baffle 30 extending at right angles to the axis thereof which deflects the inflowing 65 material and throws it toward the periphery of the casing. Any heavy waste materials will remain at the periphery of the casing, of course, 70 and will be removed through the outlet opening 27, but lighter waste materials will tend to move toward the axis of the impeller where they will gradually float into one of the passages 31 between the baffle 30 and the shield 32 and are 75 thus conducted to the outlet opening 28. The

shield 32 is provided primarily to protect such waste materials, once they have entered the passage 31, from eddies produced by the movement of the scrapers along the screen 16.

The inlet opening to the casing, designated 5 generally by numeral 33, has mounted therein a rotating unit 34 which may be called a rotating or spinning screen for the inlet opening. This unit serves to limit the size of pieces of material tending to enter the apparatus and thereby 10 eliminates many of the difficulties otherwise encountered in handling large pieces of material within the apparatus. In addition it performs a disintegrating and defibering action which enables the machine, if desired, to treat raw stock 15 which has not previously been treated in a breaker beater. The said unit is cylindrical in shape and is rotated by the shaft 6 by means of a key-way 35. It is provided with a plurality of passages 36 separated by partitions 37, the 20 lower ends 38 of which may be curved or scoop shaped as illustrated in Figure 8 in order to improve the hydraulic efficiency. The unit is held in position by a ring 40, and is caused to bear against the ring 40 by a rubber washer 41 located between the unit and the nut 42 on the shaft 6. By adjusting the thickness of the rubber washer or by placing shims between the washer and nut, the pressure of the unit against the ring 40 may be adjusted as desired. Preferably the ring 40 is provided with an eccentrically curved edge 43 which overlies the openings to the passages 36 thus providing a shearing action which is extremely effective in disintegrating solid material entering or tending to enter the said openings. A prong 44 may also be secured to the rotating unit, which said prong additionally assists in disintegrating solid material and particularly any large sheets or lumps of solid material which might tend to cover the 40 inlet opening and cut off the flow of material.

As illustrated in Figure 1, the machine is mounted above a chamber 50 to which material may be supplied through the pipe 51, but it will be understood that the machine may be mounted 45 on any suitable container or that the material to be treated may be supplied to the inlet opening in any suitable manner.

Near the upper end of the shaft 6, and adjacent the gland packing 53, is provided a cylindrical groove 54 communicating with a pipe 55 to which water under pressure may be supplied in order to provide a water seal for the upper end of the shaft. Another groove 56 is provided around the member 34 and the said groove 55 communicates with the pipe 57 which supplies water under pressure to provide a water seal. It will be understood that these water seals serve to prevent fibrous material from entering the passages between bearing surfaces, but they may 60 also be used to adjust the consistency of the stock which is being treated in the impeller chamber, for by increasing the water pressure, or by increasing the clearances, if necessary, the material in the impeller chamber may be diluted 65 to any degree necessary or desirable.

It will be understood that the invention may be variously modified and embodied within the scope of the subjoined claims.

I claim as my invention:

1. In an apparatus of the class described, in combination, a casing, a flat screen in said casing, said casing having inlet and outlet openings on opposite sides of said screen, said screen having small apertures therein for screening pur- 75

poses and a larger aperture therein for recycling screened material, and an impeller rotatable within said casing in close proximity to said screen, the axis of said impeller being perpendicular to said screen, said large screen apertures being located nearer to said axis than the majority of said small apertures.

2. In an apparatus of the class described, in combination, a casing, a flat screen in said casing, said casing having inlet and outlet openings on opposite sides of said screen, said screen having small apertures therein for screening purposes and a larger aperture therein for recycling screened material, a valve controlling said aperture, and an impeller rotatable within said casing in close proximity to said screen, the axis of said impeller being perpendicular to said screen, said large screen apertures being located nearer to said axis than the majority of said small apertures.

3. In an apparatus of the class described, in combination, a casing, a flat screen in said casing, said casing having inlet and outlet openings on opposite sides of said screen, and an impeller rotatable within said casing in close proximity to said screen, the axis of said impeller being perpendicular to said screen said casing also having two outlet openings for unscreened material, one of said openings being located at the periphery of said casing beyond the outer edge of said screen, and the other of said openings being located near the axis of said impeller beyond the inside edge of said screen.

4. In an apparatus of the class described, in combination, a casing, a flat screen in said casing, said casing having inlet and outlet openings on opposite sides of said screen, an impeller rotatable within said casing in close proximity to said screen, the axis of said impeller being perpendicular to said screen, said casing also having two outlet openings for unscreened material, one of said openings being located at the periphery of said casing beyond the outer edge of said screen, and the other of said openings being located near the axis of said impeller beyond the inside edge of said screen, and means forming part of said impeller providing a passage to said second outlet opening.

5. In an apparatus of the class described, in combination, a casing, a flat screen in said casing, said casing having inlet and outlet openings on opposite sides of said screen, an impeller rotatable within said casing in close proximity to said screen, means mounted in said inlet opening and subdividing said inlet opening into a plurality of smaller openings, said means being rotatable with said impeller, and means cooperating with the edges of said openings to provide a shearing action to cut material entering said openings and to keep said openings clear.

6. In an apparatus of the class described, in combination, a casing, a flat screen in said cas-

ing, said casing having inlet and outlet openings on opposite sides of said screen, an impeller rotatable within said casing in close proximity to said screen, means mounted in said inlet opening and rotatable with said impeller and having edges to engage and disintegrate solid material entering said inlet opening, a ring at the mouth of said inlet opening, said ring having an edge extending across said impeller edges, and resilient means to hold the edges of said disintegrating means in shearing relation with the edge of said ring.

7. In an apparatus of the class described, in combination, a casing, a flat screen in said casing, said casing having inlet and outlet openings on opposite sides of said screen, an impeller rotatable within said casing in close proximity to said screen, means mounted in said inlet opening and rotatable with said impeller and having edges to engage and disintegrate solid material entering said inlet opening, a ring at the mouth of said inlet opening, said ring having an edge extending across said impeller edges, resilient means to hold the edges of said disintegrating means in shearing relation with the edge of said ring, and means to adjust the pressure exerted by said resilient means.

8. In an apparatus of the class described, a casing, a fixed flat screen in said casing, said casing having inlet and outlet openings on opposite sides of said screen, an impeller rotatable within said casing in close proximity to said screen, said impeller having radial vanes, said intake opening being coaxial with said impeller, said casing also having two outlet openings for unscreened material, one of said openings being located at the periphery of said casing beyond the ends of said vanes, and the other of said openings being located near the axis of said impeller, and a baffle on said impeller extending at right angles to the axis thereof and adapted to prevent direct flow of material from said intake opening to said second outlet opening.

9. In an apparatus of the class described, a casing, a fixed flat screen in said casing, said casing having inlet and outlet openings on opposite sides of said screen, an impeller rotatable within said casing in close proximity to said screen, said impeller having radial vanes, said intake opening being coaxial with said impeller, said casing also having two outlet openings for unscreened material, one of said openings being located at the periphery of said casing beyond the ends of said vanes, and the other of said openings being located near the axis of said impeller, a baffle on said impeller extending at right angles to the axis thereof and adapted to prevent direct flow of material from said intake opening to said second outlet opening, and means forming part of said impeller providing an enclosed passage to said second outlet opening.

EDWIN COWLES.
